(57) **CLAIM**

We claim the ornamental design for a door template, as shown and described.

DESCRIPTION

FIG. 1 is a left side perspective view showing an embodiment of our new design for a door template;

FIG. 2 is a front view showing our new design shown in FIG. 1;

FIG. 3 is a right side view showing our new design shown in FIG. 1;

FIG. 4 is a left side view showing our new design shown in FIG. 1;

FIG. 5 is a bottom view showing our new design shown in FIG. 1;

FIG. 6 is a top view showing our new design shown in FIG. 1;

FIG. 7 is a back view showing our new design shown in FIG. 1; and,

FIG. 8 is a right side perspective view showing our new design shown in FIG. 1.

The broken line showing of structural features is included for the purpose of illustrating non-claimed subject matter and forms no part of the claimed design.
